5 Sheets-Sheet 2

<img alt="A detailed schematic diagram of a seismic detection and recording system. The top section shows a timeline with three detector signals (D-210, D-110, D-10) and a corresponding waveform on a recorder. The waveform is labeled with 'DIRECT ARRIVAL' (short spikes), 'FALSE SIGNALS' (smaller spikes), and 'REFLECTED EVENTS' (longer spikes). Below this is a detailed circuit diagram. It features three detectors (210, 110, 10) connected to a logic section with various resistors (e.g., 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 474, 475, 476, 477, 478, 479, 479, 480, 481, 482, 483, 484, 485, 486, 487, 488, 489, 489, 490, 491, 492, 493, 494, 495, 496, 497, 498, 499, 499, 500, 501, 502, 503, 504, 505, 506, 507, 508, 509, 509, 510, 511, 512, 513, 514, 515, 516, 517, 518, 519, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1178, 1179, 1180, 1181, 1182, 1183, 1184, 1185, 1186, 1187, 1188, 1189, 1189, 1190, 1191, 1192, 1193, 1194, 1195, 1196, 1196, 1197, 1198, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1278, 1279, 1280, 1281, 1282, 1283, 1284, 1285, 1286, 1287, 1288, 1289, 1289, 1290, 1291, 1292, 1293, 1294, 1295, 1296, 1296, 1297, 1298, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1378, 1379, 1380, 1381, 1382, 1383, 1384, 1385, 1386, 1387, 1388, 1389, 1389, 1390, 1391, 1392, 1393, 1394, 1395, 1396, 1396, 1397, 1398, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1478, 1479, 1480, 1481, 1482, 1483, 1484, 1485, 1486, 1487, 1488, 1489, 1489, 1490, 1491, 1492, 1493, 1494, 1495, 1496, 1496, 1497, 1498, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1578, 1579, 1580, 1581, 1582, 1583, 1584, 1585, 1586, 1587, 1588, 1589, 1589, 1590, 1591, 1592, 1593, 1594, 1595, 1596, 1596, 1597, 1598, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1678, 1679, 1680, 1681, 1682, 1683, 1684, 1685, 1686, 1687, 1688, 1689, 1689, 1690, 1691, 1692, 1693, 1694, 1695, 1696, 1696, 1697, 1698, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1778, 1779, 1780, 1781, 1782, 1783, 1784, 1785, 1786, 1787, 1788, 1789, 1789, 1790, 1791, 1792, 1793, 1794, 1795, 1796, 1796, 1797, 1798, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, METHOD OF AND APPARATUS FOR SEISMOGRAPH PROSPECTING

Engelhardt A. Eckhardt, Pittsburgh, and Gary Muffy, Penn Township, Allegheny County, Pa., assignors to Gulf Research & Development Company, Pittsburgh, Pa., a corporation of Delaware

Application March 14, 1939, Serial No. 261,854

10 Claims. (Cl. 181—0.5)

This invention or discovery relates to methods of and apparatus for seismograph prospecting; and it comprises a method of seismograph prospecting including the steps of establishing a plurality of seismic wave detectors at spaced points in the earth, establishing a recording element therefor, generating a seismic wave impulse at a point spaced from the detectors, transmitting signals from one detector only to said recording element at the time of arrival of the first refracted wave at said detector and transmitting signals from a plurality of detectors to said recording element at the time of arrival of reflected waves at said detectors; and it further comprises apparatus adapted for carrying out such method and including means for generating seismic waves in the earth, a group of detectors for detecting seismic waves, amplifying and recording means, and switching means between the detectors and the recording means constructed and arranged to connect one of the detectors to the recording means for unobstructed receipt of the first refracted wave to arrive at said detector, and to connect a plurality of detectors to the recorder means for receipt of reflected waves; all as more fully hereinafter set forth and as claimed.

One object of the invention is the provision of a method of reflection seismograph prospecting with the aid of a plurality of detectors and a single recording element, in which a single detector is connected to the recorder for reception of the refracted wave and a plurality of detectors are connected to the recorder for reception of the reflected waves, whereby a clear record of both types of waves is obtained in a simple manner.

Another object of the invention is the provision of a seismograph prospecting system including methods of and means for systematically recording the signals from a plurality of seismic detectors in such sequence as to yield in the record the most information from a given number of detectors. Another object is the provision of a remote controlled switching system for detectors for systematically connecting the detectors to the recorder during the receipt of seismic waves in such a way as to receive both the direct arrivals, and later arrivals, separately and without mutual obstruction. Another object is the provision of a switching system in which the detectors are automatically connected to or disconnected from a recorder in a systematic manner, upon arrival of some particular wave at each detector. Another object is the provi-

sion of a seismograph prospecting system including a group of detectors and an electronic circuit for each detector, wherein the first wave arriving at a detector is received and recorded by itself, the other detector circuits remaining out of action, and then all the detector circuits are rendered sensitive for receipt and recording of later arriving waves.

In seismograph prospecting, an explosive charge is set off at some point in the earth, and seismic waves are propagated from this shot point in all directions. Some waves travel along near the surface of the earth without penetrating downward any great distance. Other waves are reflected and refracted at interfaces between deep buried rock strata of different wave-transmitting characteristics and return to the surface of the earth in the general neighborhood of the shot point. In the reflection method of seismograph prospecting, a plurality of seismic detectors or seismophones are placed in the earth at spaced distances, so located with respect to the shot point as to receive waves reflected upward from deep strata. The detectors are arranged to give a fluctuating electrical signal which corresponds to the amplitude of the earth tremors at the detector, or to the velocity or the acceleration of the tremors, depending upon the type of seismophone employed. The electrical signal is amplified and is recorded for study. The record is made by applying the amplified detector signals to oscillograph elements (sensitive galvanometers capable of registering rapid vibrations) arranged to produce a trace on a moving band of photographic paper or film.

In reflection seismograph work, it is also necessary to record and study the so-called direct waves (shallow refracted waves which travel more or less directly from the shot point to the detectors near the surface of the earth), in order to make corrections for the characteristics of the weathered layer of rock just below the earth's surface. This weathered layer, which may be of thickness from zero to many feet, has wave-transmitting characteristics markedly different from those of the underlying more compact rock, and its effect on waves reflected up from deep strata must be measured and compensated for. The direct wave is ordinarily the first to arrive at the detector positions.

In good current reflection seismograph practice, a plurality of series-connected, spaced detectors are employed for each of the recorder oscillograph elements, instead of a single de-

ector for each recorder element as in older practice. Several such groups are employed. The resultant output of each group of detectors is recorded as a single trace which is considered as if it were due to a hypothetical single detector centrally located in the group. This arrangement is particularly advantageous in studying the reflections from the deeper underlying strata, because it results in a clearer record of such reflections.

However, the detector grouping arrangements described are not specially satisfactory for recording the direct wave. They are no better than a single detector in obtaining data on the weathered layer. After the first arrival at the first detector, the record is obscured by the overlapping of waves received at the remaining detectors of the group. That is, by the time the direct wave reaches say the last detector of the group, other waves are being received at the other detectors which are recorded simultaneously with the first arrival. In fact, the direct wave, which is usually much more intense than any of the reflected waves, seriously obscures the record.

According to the invention, there is provided a system wherein grouped detectors are employed, but only one detector at a time is allowed to record the direct wave the other detectors of the group being connected to the recorder only after the direct wave has been received and recorded. This gives the necessary data for making the weathering correction and at the same time the record for both the refracted wave and the reflected waves is much improved. In one form of the invention, the first arrivals at a plurality of detectors are recorded separately, each detector in turn being momentarily connected to the recorder during receipt of the direct wave at the detector, then disconnected so that the signal from the next seismophone will not be obscured, and finally connected again to the recorder in time for receipt of the several reflected waves. Such arrangement gives the greatest amount of data possible, with a given number of detectors. The invention is also susceptible of other applications, as will be clear from the extended description to follow.

In the accompanying drawings there are shown diagrammatically four examples of specific embodiments of apparatus within the purview of the invention and useful in the performance of the method, and diagrams illustrative of the actions taking place. In the drawings—

Fig. 1 is a view of the complete apparatus organization set up in the field;

Fig. 2 is a detailed diagram of one form of apparatus including mechanical switching means;

Fig. 3 is a chart illustrating the detector switching as obtained with the apparatus of Fig. 2;

Fig. 4 is a diagram of a modification of Fig. 2, in which the switching mechanism is under automatic electrical control;

Fig. 5 is a diagram of an electronic switching system;

Fig. 6 is a chart illustrating the actions taking place in the utilization of the apparatus of Fig. 5;

Fig. 7 is a diagram of a modified form of the apparatus of Fig. 5;

Fig. 8 is a diagram of a modification of the apparatus of Fig. 2; and

Fig. 9 is a schematic showing of the system of the invention set up in the field.

Referring to the drawings, Fig. 1 diagrams a typical apparatus embodiment of the invention

in a simple form as including detectors arranged in two groups of three (18, 118 and 218, 19', 119' and 219') switching apparatus 11 and 11' and amplifiers 12 and 12', one for each group, and a recorder 13. The switching apparatus is located near the detectors and connection is made to the amplifiers by cables 196 and 196' (see also Fig. 9). The detectors are set up at or near the surface of the earth, and receive waves from a shot 14 fired by a blasting machine 15. The shot is usually located at the base of the weathered layer of rock 16 near the surface of the earth. Waves are propagated from the shot in all directions, as indicated by rays in the figure. A so-called direct wave travels along the interface 17 between the weathered layer and a lower, more consolidated layer 18, and reaches the several detectors by bent paths as indicated at 19. The direct wave usually reaches the detector first. Other waves, indicated by rays 20, penetrate into the earth and reach the detectors after reflection from deep strata interfaces 21 and 22. Generally these reflected waves arrive at the detectors later than the direct wave.

One form of switching apparatus 11, arranged for utilization with three detectors, is shown in Fig. 2. The apparatus includes the elements surrounded by the dot-dash line as shown, and is conveniently placed at or near the detectors as indicated in Fig. 1; at a location which may be several hundred or thousand feet away from the amplifying and recording system. The apparatus is designed to permit connection of any one of the three detectors to the recorder, and to permit connection of all three detectors simultaneously to the recorder, as desired. A four-point double-pole switch is provided, shown as including two stationary plates 25 and 26 of insulating material, each having four contact points 27, 28, 29, 30 and 31, 32, 33 and 34, cooperating with a pair of rotary brushes 35 and 36 mounted on a shaft 31. The brushes are insulated from each other by insulation 38. Each detector has a pair of leads 39 and 40, 41 and 42, and 43 and 44 respectively, and each lead is connected to two of the contact points. This lead 39 is connected to points 27 and 30, by wires 45 and 46; lead 40 and lead 41 are connected to points 28 and 31, by wires 47 and 48; lead 42 and lead 43 are connected to points 29 and 32 by wires 49 and 50; lead 44 is connected to points 33 and 34 by wires 51 and 52. The brushes, 35 and 36, are connected to the amplifier 12 through leads 53, a transformer 54, leads 55 and a transformer 56 as shown. The amplifier is of conventional electronic type and delivers an amplified signal through leads 57 to the recorder 13, which also is of known type and includes an oscillograph element 60 provided with a mirror (not shown), a lamp 62, a moving photographic paper surface 63 and a motor 64 for moving the paper. The oscillograph element on actuation causes a focused beam of light from the lamp to move over the photographic paper and make a trace 65. The blasting machine 15 is connected to the shot 14 (a charge of dynamite with an electric blasting cap 66) through leads 67 and an oscillograph element 68 is connected into this shot-firing circuit, through leads 69 with a large protective shunt resistance 68 arranged as shown, so that on firing the shot a fluctuation will be produced on the paper by oscillograph 61 which will allow the instant of firing the shot to be determined on the record.

The means for actuating the multi-point switch

are as follows: Shaft 37 is urged in a clockwise direction by a torsion spring 75, the brushes normally resting against stops 76 on plates 25 and 26. A polarized relay is provided including a triple pole piece 77, a T-shaped permanently magnetized armature 78 arranged for rotation about a pivot 79 and normally held in the neutral position shown by a pair of springs 80 and 81, and having a pawl 82 engaging a ratchet 83 on shaft 37. Pole piece 77 is energized by a coil 84 which is connected through a reversing switch 85 with a battery 86, by means of lead 87 (from the coil to a center tap in transformer 54), lead 88 (to one side of the reversing switch) and lead 89 (from the other side of the reversing switch to a center tap on transformer 56). Upon energization of coil 84, both the upper and the lower poles of pole piece 77 are energized, with like polarity, N or S depending on the position of switch 85. A cooperating detent mechanism is provided, including a bell crank 100 with detent arm 101 engaging the teeth of ratchet wheel 83 and an arm 102 pressed upward by a spring 104. A stop 103 limits the movement of arm 101. A depending post 99 on member 78 is arranged to engage arm 102 upon anti-clockwise movement of member 78.

In practical embodiments, wires 55 and 88 are enclosed in a cable 188 of suitable length reaching from the detector location to the recording location (Fig. 9). The cable may be several hundred or thousand feet long. The arrangement of wires 55 and 88 is in the form of a phantom circuit, whereby actuation of the magnetic switch 77, 78, 84 does not interfere with the functioning of the detector-amplifier circuit.

With reversing switch 85 in one position, the upper end (N) of the T-shaped member 78 is drawn toward the pole piece 77 and ratchet 83 is moved in an anti-clockwise direction. Detent 101 holds the ratchet wheel against reverse movement. By momentarily opening and closing the switch the proper number of times, any one of the detectors can be connected to the amplifier. With the reversing switch 85 in its other position, the polarity of pole piece 77 is reversed, and by momentarily closing the switch to this position, detent arm 101 releases the teeth of ratchet wheel 83, allowing the shaft 37 to rotate clockwise under the influence of spring 75. In the position shown, all three detectors are connected to the amplifier in series. By actuating switch 85 until brushes 35 and 36 are caused to make contact at points 29 and 33, only the right-hand detector 10 is connected to the amplifier. When brushes 35 and 36 contact points 28 and 32, only the central detector 110 is connected, and when brushes contact points 27 and 31, only the left-hand detector 210 is connected.

In operation, assuming the right-hand detector 10 to be the detector nearest the shot point (cf. Fig. 1), switch 85 will first be operated manually to bring brushes 35 and 36 in contact with points 29 and 33, so that only this first detector is connected with the recorder when the direct wave reaches it. When switch 85 is reversed momentarily the shaft 37 is brought back to the position shown in Fig. 2 under the influence of spring 75. The switch 85 can then be manipulated again to connect some other detector, for the next shot. When the position shown in Fig. 2 is attained, all detectors are connected to the amplifier in series. The switching device of Fig. 2 can thus be used as a remote-operated manual switch. It forms a very convenient way of shift-

ing the detector connections at will and saves the services of an extra operator which might be required were the detector connections to be changed at the recording point or were extra cables to be run.

When the time interval between the first arrivals and the reflection arrivals is sufficiently great, the switching mechanism of Fig. 2 can be operated between the time of the first arrival and the time of the reflection arrival, so as to record as a single oscillograph trace the first arrival, and reflection arrivals, from a single shot. The functioning of the system of Fig. 2 in such procedure is diagrammed in Fig. 3, which shows by hatching the "on" and "off" intervals during which the several detectors are connected to the amplifier and recorder. As shown, initially only detector 10 is connected, so as to receive the direct-wave arrival (first arrival) under optimum conditions. Then the other two detectors 110 and 210 are connected, to record the reflection arrivals. The relative times at which the direct wave and the reflected waves arrive are indicated in the lower part of Fig. 3, which is a reproduction of an oscillograph trace such as is obtained with the apparatus of the invention when the switching from the first detector to all the detectors is made between the instants when the direct wave and the reflected waves arrive. The switching usually introduces some false signals in the record as indicated in Fig. 3, but they are characteristic in form and easy to distinguish, and moreover they arrive at a time when no important waves are being received; so there is no confusion from this source.

Fig. 4 shows a modification of the apparatus of Fig. 2, having two automatic controls for the multi-point switch, either of which can be employed according to the particular circumstances encountered. As shown, magnetic means are provided for actuating crank 100, comprising an electromagnet 105 adapted to draw armature 102 so as to release the ratchet. The magnet is energized through leads 107 by the amplifier output, rectified at 106, a switch 108 being interposed as shown. Wires 107 are conveniently included in cable 188 along with wires 88 and 85. With the arrangement shown, the first arrival (direct wave) causes an impulse in the amplifier output, a portion of which is applied as rectified D. C. current to magnet 105, thereby releasing the ratchet and allowing the multi-point switch to connect the three detectors in series, so that by the time the reflected waves begin to come in all three detectors are connected to the recorder.

The system is shown with an alternative control adapted to actuate the multi-point switch a predetermined brief interval after the firing of the shot, which is more convenient in some cases. As shown, a bimetallic (thermostat) element 112 is provided, adapted to be heated by a heating resistor 113 in the blasting cap circuit (leads 67), which bimetallic element opposes a pair of contact points 114 and 115 and thereby makes up a delaying switch. The switch is in series, through a double-pole, double-throw switch 185, with leads 88 and 89 and the battery 86, so that, assuming switch 185 to be thrown to the left and shunt switch 116 opened, upon firing of the shot, first only one of the detectors is connected to the recorder, but as soon as switch 112 closes, the circuit through coil 87 is completed and switching takes place. By throwing the switch 185 to the right, the multi-point switch

can be returned to starting position. The time delay of thermal switch 112 can be adjusted by means of an adjustable resistor 118 shunted across heating resistor 113. If this thermal switch control is not to be employed, switch 116 is simply closed.

Fig. 5 shows an electronic detector switch arrangement, which is capable of carrying out the switching with exceptional smoothness and regularity. Four detectors, 10, 110, 210 and 310 are shown, each connected to an amplifier 12, 112, 212 and 312, the output of each amplifier being applied to the grid 120 of a control tube, 23, 123, 223 and 323. Each tube has a cathode 121 grounded at 122, and a plate 122. Four transformers are provided, 125, 126, 127 and 128, the secondaries 129 of which are of identical construction and are connected in series to recorder 13. (The usual filters, extra stages of amplification, etc., can be interposed between the transformers and the recorder if desired). Each transformer has an ordinary input winding together with an extra winding or windings to furnish control voltages. Thus transformer 125 has a primary 130 and two auxiliary windings 131 and 132; transformer 126 has a primary 133 and an auxiliary winding 134; transformer 127 has a primary 135 and an auxiliary winding 136, and transformer 128 has a primary 137 and an auxiliary winding 138. For the plate circuits, one side of each of the primaries 130, 133, 135 and 137 is connected, through a battery 140, with ground at 141, while the other side of each of the primaries 130, 133, 135 and 137 is connected to the plate 122 of the corresponding tube, 35 as shown. The other electrical connections are as follows: auxiliary windings 131, 132, 134, 136 and 138 respectively have capacitances 142, 143, 144, 145 and 146, and resistances 147, 148, 149, 150 and 151, shunted thereacross to form filters, and rectifiers 152, 153, 154, 155 and 156 in series as shown. One side of winding 131 is connected, through rectifier 152, a battery 166 and a resistor 161, with the grid of tube 23. The other side of winding 131 is connected by a variable tap 162 with resistor 151. Winding 132 is connected between the grid 120 of tube 123, and a variable tap 163 to resistor 151. Winding 134 is connected between the grid 120 of tube 223 and a third variable tap 164, on resistor 151. Winding 136 is connected to the grid 120 of tube 323, and to ground. Winding 138 is connected to the resistor 151 and also to the cathode of tube 323. Batteries 166, 167 and 168, and resistors 169, 170 and 171, are included in the circuits of windings 132, 134 and 138, as shown.

The mode of operation of the system of Fig. 5 is as follows: Assuming the system to be set up, waiting for the shot to be fired, only the first tube, 23, is in operative state, the other tubes being biased beyond cutoff and therefore inoperative. Then when the first wave from the shot point reaches detector 10, the signal from the detector is amplified by the corresponding tube 23 and the amplified signal is delivered to the recorder. However, immediately on receipt of the signal, a potential appears at transformer control winding 131. This potential is rectified at 152, and filtered at the resistance-capacitance combination 147, 142, and is applied to the grid 120 of the tube (23) to bias it. Thus a short interval after receipt of the first arrival at tube 23, the tube is rendered inoperative or incapable of transmitting signals by being biased beyond cutoff, so the detector is in effect cut off 75

from the recorder. The resistance of the rectifier 152 and resistor 147 and the capacitance of condenser 142 are selected so as to let tube 23 remain inoperative over the required short time interval. In the meantime, while tube 23 is amplifying signals a second control voltage is furnished at transformer winding 132, and this voltage, rectified at 153 and filtered at 148 and 149, is applied to the grid of tube 123 in such way as to render the grid less negative, i. e. to unbias it, whereby tube 123 is rendered capable of amplifying the first arrival at detector 110. Tube 123 stays "on" for a brief instant and then is cut off, after tube 23 goes out of action as described and the unbiasing voltage from winding 132 is no longer available. The values of the components of filter 148, 149 are selected to keep tube 123 on the proper length of time.

Tube 123 in turn cuts in tube 223. Tube 223 cuts in tube 323. The time constant of filter 145, 150 is made much larger than that of the first two filters described, so that tube 323 stays on for several seconds to insure recording of the first arrival and all the reflected events.

When tube 323 receives its first arrival from the detector 310, winding 138 produces a control voltage, which is rectified at 156 and filtered at 146, 151, and is applied to the first three tubes (voltage being taken to the grid circuits of these tubes from resistance 151 at taps 162, 163 and 164), which makes the other three tubes active again for reception of the reflected waves. Filter 146, 151 has a long time constant of discharge to keep the tubes sensitive until all reflections arrive; usually a matter of a few seconds. After all waves have been received, the voltages in the various filters gradually die out, restoring the system to its original state.

Fig. 6 illustrates the functioning of the system of Fig. 5. Tube 23 is operative in the beginning. When the direct arrival reaches detector 10, it develops an electrical signal which is amplified by tube 23 and recorded as indicated at DA in Fig. 6. The tube then goes out of action and tube 123 goes into action to receive the direct arrival DA' at detector 110. Tube 123 goes out of action and tube 223 goes into action to receive the direct arrival DA'' at detector 210. Tube 223 then goes out of action and tube 323 goes into action to receive direct arrival DA''' at detector 310 and stays in operative condition. Tube 323 operates to bring the first three tubes into action again so that all the tubes are in operative state when the reflections come in, as shown. In due course, the transient control voltages die out, restoring the system to its initial state as indicated at the extreme right of Fig. 6.

While the signals are shown as applied to a single recorder, separate recorders can of course be used if desired; a separate recorder being connected to the output winding 129 of each of the transformers 125, 126, 127 and 128. The electronic switching means of Fig. 5 is conveniently placed adjacent the amplifying and recording means, as shown.

The control voltage appearing across the transformer winding 131 is, as described, used to bias the grid of tube 23 so as to render the tube inoperative. This is similar in effect to automatic volume control, except that the amplifiers 23, 123, 223, and 323 are more abruptly and completely cut off or on than with usual automatic-volume-controlled amplifiers. It is sometimes advantageous to provide additional bias control to the tubes in amplifiers 12, 112, 212, and 312,

as the control effect can be improved by increasing the number of tubes to which bias is applied. Figure 7 is a partial view showing a modification of Figure 5, in which instead of a simple amplifier 12 there is used an amplifier 412 arranged for volume control in accordance with an applied grid bias voltage. Amplifier 412, which is of a general type known per se in radio circuits and which requires no detailed description, includes a preamplifier tube 413 and an amplifier tube 414. Grids 415 and 416 of these tubes are arranged to receive bias voltage through lead 417 from rectifier 412 and transformer winding 131. In operation, on development of a control voltage in transformer winding 131 (as described in connection with Figure 5) a part of the control energy serves to bias the grid 128 of tube 28 to secure the desired throttling action and the remainder of the control energy to bias grids 415 and 416 of amplifier 412 and thereby bring about additional throttling effect. By causing the control voltage to affect three tubes in the manner described, the controlling action is sharper than when only one tube is affected. Figure 7 shows only one detector-amplifier-control-tube circuit; the other amplifiers 112, 212, and 312 of Figure 5 can be modified exactly as shown in Figure 7.

Fig. 8 shows a modification of the apparatus of Fig. 2 which is adapted to shift the detector connections so that the detectors receive the direct wave successively and individually, and all the detectors receive the reflected waves. The system of Fig. 8 thus performs a function similar to that of the apparatus of Fig. 5. Referring to Fig. 8, three detectors 10, 110 and 210 are shown as in Fig. 2; and multipoint switches 25 and 26, electromagnetic ratchet mechanism 83, 78, 84, amplifier 12, recorder 13 and shot 14 are all provided as described in connection with Fig. 2. A third multipoint switch, having a stationary plate 188 with contacts 181, 182, 183, 184 and 185 is provided. Contacts 182 to 185 are dummies. Shaft 37 is prolonged as shown and carries a rotary brush or arm 186 engaging the contacts as shown. A pawl 180 and actuating electromagnet 185 are provided as in Fig. 4. The magnet is in circuit through leads 189 and 190 with a battery 187 and switch arm 186. A control switch 188 is connected in parallel with leads 188 and 190 so that by closing the switch the pawl 180 will be actuated. Control current leads 187 from the amplifier output (cf. Fig. 4) are connected to coil 84 of the ratchet switch 78, 82, 84 through a rectifier 8. A switch 181 is connected across the amplifier input to allow the operator to actuate this ratchet switch. Closing this switch results in production of a current in leads 187, of sufficient strength to operate the ratchet switch, due to thermal or contact potentials.

In operation, switch 188 is first closed for a moment to bring the rotary switch arms 35, 36 and 186 to their extreme right-hand positions resting against stops 78. Switch 181 is then closed and opened one or more times to move the switch arms 35, 36 and 186 to the desired detector position; e. g. to connect detector 10 to the amplifier. Upon the firing of the shot the rest of the operations are performed automatically. Each direct arrival produces a current in leads 187 which serves to move switch arms 35, 36 and 186 to the next succeeding contact points; viz. the arms first move from points 33, 29 and 184, to points 32, 28 and 183. The last arrival brings the arm 186 to contact point 181, thereby releasing pawl 180 from ratchet wheel 83 and allowing

shaft 37 to spring back to its original position, viz. the position shown in Fig. 8, where all the detectors are connected to the amplifier for receipt of the reflected waves. If the reflections arrive simultaneously, the selector switch would then move one step counter-clockwise and the system is ready for a new operation.

Fig. 9 is a diagrammatic showing of the system of the present invention as set up in the field, based on Fig. 1. While the drawing is not to scale, it shows in a clear manner the problem encountered in the seismograph prospecting art, and the solution of it according to the present invention. The shot 14 is ordinarily at a distance of from several hundred yards to several miles, from the nearest of the detectors 10, 110, etc., and the complete array of detectors (six are shown) extends over a distance of from several hundred to several thousand yards. The amplifiers 12 and recorder 13 are mounted in a truck 195 near the detectors, and the truck will ordinarily be several hundred or thousand yards from the farthest detector (detector 10 in the figure). If each detector were connected independently to the amplifier, there would have to be twelve wires. But according to the invention the only wires that have to be laid great distances along the ground are the two cables 196 and 196'. Thus the job of laying cables is just as simple in the present invention as in conventional prospecting systems without any switching provisions. Wires from the blasting machine as shown at 88 (or a corresponding radio transmitting circuit) are provided in the present system as in all other seismograph prospecting systems so as to provide for recording of the instant of firing the shot.

While the invention has been described in reference to reflection seismograph shooting, it is also applicable to refraction shooting, wherein similar advantages accrue. In such utilization the detectors are of course spaced farther from the shot point.

In the embodiments shown, the detectors are arranged for series connection when in combination. They can also be connected in parallel or series-parallel, and each detector can be replaced if desired by a plural combination of detectors so arranged as to act as one. The invention is useful with various known geometrical arrangements of detectors and is not limited to any particular number of detectors. Radio transmission can be employed in lieu of wire transmission if desired.

With the aid of the invention there is obtained with a single recording element 80 (in other words, with a single trace), a record which gives just as much information as is obtainable in ordinary systems using a plurality of recording elements; the record being indeed substantially clearer by virtue of the separation of the recording of the refracted and reflected waves.

What we claim is:

1. In seismograph prospecting methods wherein in the output of a plurality of seismic detectors is applied to a single recording element, the improvement which comprises locating a plural group of electric signal producing seismic wave detectors at spaced points in the earth, generating a seismic wave impulse at a point spaced from the group of detectors so as to cause propagation of seismic waves undergoing reflection and refraction in the earth, maintaining electrical connection between only one of said detectors and the recording element during the arrival of the

first refracted wave at said detector and, before reflected waves arrive at the detectors, establishing electrical connection between a plurality of the detectors and the recording element; whereby the first refracted wave is detected individually by a detector and the reflected waves are detected by a plurality of detectors.

2. A seismograph prospecting apparatus for receiving and recording seismic waves comprising a plurality of detectors arranged to detect seismic waves and to produce electrical signals corresponding thereto, amplifying and recording means for said signals, and electronic switching means between the detectors and the recording means comprising a vacuum tube amplifying circuit for each detector, the circuit for the detector nearest the shot point being normally adjusted to amplify the signals from that detector and the circuits for the remaining detectors being normally adjusted so as to be insensitive, electrically operable sensitivity regulating means in each circuit, a control circuit receiving signal energy from the first detector circuit and supplying it to said first regulating means, to render said circuit insensitive upon appearance of signal energy due to the first seismic wave to arrive at the detector, a control circuit receiving signal energy from the first detector circuit and supplying such energy to the sensitivity regulating means of the second detector circuit in such sense as to render said second detector circuit momentarily sensitive, and a control circuit receiving signal energy from the last detector circuit and supplying it to the sensitivity regulating means in all the preceding circuits in such sense as to render all the circuits sensitive in time for receipt of later reflected arrivals at the several detectors.

3. A seismograph prospecting apparatus for receiving and recording seismic waves comprising a plurality of detectors for detecting seismic waves and producing electrical signals corresponding thereto, amplifying and recording means for said signals, and electronic switching means between the detectors and the recording means; said electronic switching means comprising a vacuum tube amplifying circuit for each detector, the first circuit normally being adjusted so as to be sensitive and the succeeding circuits normally adjusted so as to be insensitive, a transformer for each amplifier circuit having a primary winding receiving the output of said circuit and a secondary winding connected to the recording means, an additional winding associated with the primary of the first amplifier circuit and means for applying energy from said additional winding to the first amplifier circuit in such direction as to render it insensitive, a plurality of control windings, one coupled with each of the transformer primaries except the last amplifier transformer primary, means for applying energy from each of said control primaries to the succeeding amplifier circuit in such direction as to render said succeeding amplifier circuit momentarily sensitive, an additional control winding coupled with the last transformer primary and means for applying energy from said last control winding to the preceding amplifier circuits, in such direction as to render them sensitive again.

4. In a seismograph prospecting apparatus comprising means for generating seismic waves which penetrate in the earth and undergo reflection and refraction, a plural group of electrical signal producing seismic wave detectors spaced from said generating means, amplifying and recording means, and circuits connecting the

detectors with the amplifying and recording means; the improvement which comprises switching means in and controlling said circuits, adapted in one position to connect one of the detectors to the amplifying and recording means and in another position to connect a plurality of the detectors to the amplifying and recording means, means adapted on actuation to shift the switching means from the first position to the second and means for actuating said means at a time subsequent to receipt of the first refracted wave at the detector nearest the generating means but before receipt of reflected waves at the detectors.

5. A seismograph prospecting apparatus comprising in combination a plural group of electrical signal producing seismic wave detectors arranged in the earth, signal amplifying and recording means at a point spaced from the group of detectors, a switch having a plurality of contact elements greater than the number of detectors and a contact member movable with respect to said elements; circuits connecting the detectors separately to a plurality of the contact elements, a circuit connecting the detectors as a group to a pair of the contact elements, and a circuit connecting the contact member with the amplifying and recording means; electrically operable actuating means for the contact member, and control means for said electrically operable means, located adjacent the amplifying and recording means, for operating the switch in some positions thereof to connect the detectors successively and individually to the amplifying and recording means, and in one position thereof to connect all the detectors to the amplifying and recording means.

6. A seismograph prospecting apparatus comprising a source of seismic waves in the earth, a plural group of electrical signal producing seismic wave detectors spaced at various distances from the source, signal amplifying and recording means, a separate circuit for each detector connecting the detector with the amplifying and recording means, adjusting means for the first detector circuit adapted to maintain the circuit normally sensitive, adjusting means in each of the succeeding detector circuits adapted to render the circuit normally insensitive, control means responsive to signal energy and adapted to render the first detector circuit insensitive shortly after receipt of the first seismic signal thereat, a plurality of energy-supplying control circuits, one connecting each detector circuit with the adjusting means of the succeeding circuit and adapted to render the succeeding circuit sensitive on receipt of signal energy, and a control circuit supplying energy from the last detector circuit to the preceding circuits and adapted to maintain such circuits sensitive over a period of time sufficient for receipt of the later arriving waves.

7. A method of seismograph prospecting comprising the steps of generating a seismic wave in the earth to propagate waves in the earth which are refracted and reflected beneath the surface of the earth, detecting waves at a plurality of points spaced in the earth such distances from the location of wave generation that the first wave to reach each of said points is a refracted wave and later waves reaching each of said points are reflected waves, recording the first refracted wave detected at at least one of said points singly while preventing during such

recording the recording of waves received at adjacent points, and combining and recording reflected waves detected at said plurality of points.

8. The method of claim 7 wherein the first refracted wave detected at only one of said points is recorded.

9. The method of claim 7 wherein the first wave reaching each of a plurality of said points is singly recorded.

10. A method which, when applied to seismograph prospecting apparatus including a plurality of detectors spaced at sufficient distances from a source of seismic waves that the first wave to reach the plurality of detectors is a re-

fracted wave and later waves reaching the detectors are reflected waves, a recorder and electrical connections between all the detectors and the recorder, consists in maintaining operative 5 electrical connection between only one of said detectors and the recorder before and during receipt of the first refraction wave at said detector and maintaining operative electrical connection between a plurality of said detectors and the recorder before and during receipt of reflected waves at said detectors.

ENGELHARDT A. ECKHARDT.
GARY MUFFLY.
